[57] CLAIM

The ornamental design for an combined dental mold and base, as shown and described.

DESCRIPTION

FIG. 1 is an exploded front elevational view of a combined dental mold and base showing my new design;

FIG. 2 is a rear elevational view thereof, the mold and base shown assembled;

FIG. 3 is an exploded right side elevational view thereof;

FIG. 4 is a left side elevational view thereof, the mold and base shown assembled;

FIG. 5 is a top plan view thereof, the mold shown separately for clarity of illustration;

FIG. 6 is a bottom plan view thereof;

FIG. 7 is a top plan view thereof, the base shown separately for clarity of illustration;

FIG. 8 is a bottom plan view thereof;

FIG. 9 is a cross-sectional view thereof, taken along line 9—9 in FIG. 7;

FIG. 10 is an exploded front elevational view of a second embodiment thereof;

FIG. 11 is a rear elevational view thereof, the mold and base shown assembled;

FIG. 12 is a top plan view thereof, the mold shown separately for clarity of illustration;

FIG. 13 is a bottom plan view thereof;

FIG. 14 is a top plan view thereof, the base shown separately for clarity of illustration;

FIG. 15 is a bottom plan view thereof; and,

FIG. 16 is a cross-sectional view thereof, taken along line 16—16 of FIG. 14.
